GOLDER P. WILSON, OF WILKINSBURG, PENNSYLVANIA, ASSIGNOR TO WESTINGHOUSE ELECTRIC & MANUFACTURING COMPANY, A CORPORATION OF PENNSYLVANIA.

RELAY SYSTEM.

1,410,538.

Specification of Letters Patent. Patented Mar. 21, 1922.

Application filed January 20, 1921. Serial No. 438,666.

To all whom it may concern:

Be it known that I, GOLDER P. WILSON, a citizen of the United States, and a resident of Wilkinsburg, in the county of Allegheny 5 and State of Pennsylvania, have invented a new and useful Improvement in Relay Systems, of which the following is a specification.

My invention relates to protective relay 10 systems and particularly to relay systems for the protection of rolling mills.

One object of my invention is to provide means for precluding the disconnection of an electrically-operated rolling-mill motor 15 from a source of energy before the operation of the rolling mill has been completed, if a fault, other than a low-resistance short circuit, should occur in the circuit that would tend to effect the disconnection of the rolling- 20 mill motor.

Another object of my invention is to provide means, of the above-indicated character, that shall preclude the disconnection of an 25 operating apparatus from an energizing source before the operation of the apparatus has been completed.

Another object of my invention is to provide means, of the above-indicated character, that shall be simple and inexpensive in construction and reliable in its operation. 30

The stopping of a rolling mill before the completion of its operation is extremely undesirable because of the damage that is normally caused by the hot metal that is being shaped or formed by the rolls of the mill. 35 If, for any reason, the mill is stopped while the hot metal is between the rolls, unless the metal is quickly removed, the uneven heating of the rolls causes them to crack. Considerable time is then required to remove the 40 rolls and the heated metal, and great expense is incurred thereby.

Upon the occurrence of a ground in the feeder circuit that supplies energy to a rolling-mill motor, it is desirable to disconnect that motor from the system until the ground may be located and cleared in order to prevent the development of a short circuit therefrom. For the reasons stated above, however, it is essential that the motor should not be disconnected before the operation of the mill has been completed.

In my co-pending application, Serial No.

410,933, filed Sept. 17, 1920, of which this is a continuation in part, I describe a relay 55 system to take care of the above-mentioned conditions.

In addition to the over load relays that are normally employed for protection against short-circuit conditions, I provide a ground 60 relay which is responsive only to currents that are caused by a ground on the circuit. Upon the occurrence of a ground, the ground relay energizes a time-limit relay, the time 65 element of which exceeds the time interval required for the operation of the rolling mill. The definite time-element relay, in turn, effects the tripping of the circuit interrupter to disconnect the rolling mill from the source of energy. 70

In the system disclosed in the co-pending application, I provide an indicating device to indicate to the operator that the circuit of his mill has become grounded. Upon the occurrence of such condition, the mill should 75 not be restarted until the fault has been cleared.

If, however, the indicating device should become faulty and fail to operate, or if the operator should neglect to heed the indication of the fault and should start the mill for another operation, the time interval of the relay might so overlap the interval between the operations of the mill that the interrupter would be tripped while the mill was 85 operating.

In order to prevent absolutely the tripping of an interrupter while the mill is operating, I provide, according to my present invention, an additional relay, that is energized 90 while the mill is operating, to maintain the tripping circuit open until the operation of the mill is completed. The mill motor is, therefore, disconnected if the time-element relay is in its operative position. 95

The single figure of the accompanying drawing is a diagrammatic view of an electrical system embodying my invention.

A source 1 of electromotive force is adapted to supply energy to a circuit 2 from 100 which energy may be supplied to a rolling-mill motor 3 through a circuit interrupter 4. The interrupter 4 is provided with a tripping device 5 having an energizing winding 6, the circuit of which is controlled by a time- 105 element relay 7.

The rolling-mill motor 3 is supplied with energy through a feeder circuit 8 that has a plurality of current transformers 9, 10 and 11 so connected thereto as to be traversed by currents that are proportional to the currents traversing the conductors of the circuit 8.

A plurality of overload relays 12, 13 and 14 are connected to the current transformers 9, 10 and 11, respectively, and a ground relay 15 is so connected in the neutral conductor joining the current transformers and the overload relays as to be traversed by only such currents as may be caused to traverse the circuit by reason of a ground thereon. The energization of the ground relay 15 effects engagement between its contact members 16 and 17, completing a circuit thereby from negative conductor 18 of a source of electromotive force 19, through the energizing winding 20 of the relay 7, to the positive conductor 21 of the source 19 of electromotive force.

The time-element relay 7 is further provided with a device 22 that embodies a time element exceeding, in value, the interval of time that is required for the complete operation of the rolling mill. An indicating device 23, such as a lamp or a bell alarm, is provided to indicate to the operator of the rolling mill that there is a ground on the feeder circuit which is connected to that rolling mill.

Simultaneously, the operator at the generating station is notified of the occurrence of a ground by an indicating device or bell alarm 24, the circuit of which is controlled by a relay 25. The relay 25 is energized from a current transformer 26 that is connected in a ground conductor 27 and is energized only upon the occurrence of a ground on the system that causes a current to traverse the ground conductor 27.

If the indicating device 23 should become inoperative and fail to indicate the occurrence of a fault, or if the operator should fail to see the indicating device 23, he might start the mill for another operation, and the operation of the relay 7 might trip the interrupter 4 while the mill would be operating.

In order to prevent such an occurrence, a relay 28 is provided that will be energized while the mill is operating to maintain the trip circuit of the interrupter open. While the motor 3 is operating, the coil 29 of the relay 28 raises the switch 30. A latch 31 maintains it in this open position until the latch is released by a reset coil 32.

The relay 7 is provided with a switch 33 and an auxiliary switch 34 that is closed prior to the closure of the switch 33 when the relay is operated.

Thus, if a ground occurs near the completion of an operation, the relay 15 causes the initiation of the relay 7. Assuming that the operator starts the mill motor for an-

other operation, the switch 34 will complete the energizing circuit of the reset coil 32 to release the relay 28 to close the switch 30. However, since the coil 29 will be energized while the motor is operating, the switch 30 will be maintained open. The latch, meanwhile, is rendered inoperative by the reset coil 32. Upon the completion of the mill operation, the switch 30 is permitted to close, and the interrupter 4 is automatically tripped. The relay 28 thus absolutely prevents the tripping of the interrupter upon the occurrence of a ground in the circuit while the mill is operating.

The alarm at a rolling-mill-operating pulpit is arranged to be energized when the ground relay 15 that is associated with that mill is energized. The relay 7 may be arranged to maintain the tripping winding 6 energized until the relay 7 is reset after the ground has been cleared, or, the relay 7 may be rendered automatically self-resetting.

It is obvious that only the rolling-mill motor which is connected to the faulty feeder will be disconnected from the circuit 2 in a system which embodies a plurality of rolling-mill motors 3. The circuit 2 may be remotely disposed with respect to the source 1 of electromotive force, as in the relation between a substation and the main generating station.

Upon the occurrence of a ground on the conductor 35, the current transformers 9 and 26 are traversed by a ground current which energizes the relays 15 and 25. The relay 15 effects the energization of the indicating device 23 at the rolling-mill-operating pulpit and also initiates the operation of the relay 7 to actuate the interrupter after an interval of time if the motor is not then operating. Simultaneously, the bell alarm 24 at the generating station is energized by the operation of the relay 25.

The disconnection of the rolling mill motor before the operation of the mill is completed is thus prevented by the relay 28 which maintains the circuit of the trip coil open while the mill is operating. The reconnection of a rolling-mill motor on a grounded feeder circuit to the supply circuit may be prevented until the relay is reset manually, if the relay 7 is arranged to maintain the tripping winding 6 of the interrupter energized.

The overload relays 12, 13 and 14 are so adjusted as to be operated by currents of extremely large values only, such as would result upon the occurrence of short-circuit conditions. Under such conditions, the operation of the motor and, consequently, of the rolling mill could not be completed, and the relays are, therefore, arranged to effect the tripping of the interrupter.

My invention is not limited to the specific arrangement or to the devices shown, as various modifications may be made therein.

without departing from the spirit and scope of the invention, as set forth in the appended claims.

I claim as my invention:—

5. 1. In an electric circuit the combination with an apparatus requiring a definite interval of time for the operation thereof and a circuit interrupter therefor, of means energized upon the occurrence of a fault in the 10 circuit for actuating the interrupter, means for controlling the actuating means in accordance with the time required for the operation of the apparatus, and means for rendering the controlling means inoperative 15 while the apparatus is operating.
2. In an electric circuit, the combination with an apparatus requiring a definite interval of time for the operation thereof and a circuit interrupter therefor, of means energized upon the occurrence of a fault in the 20 circuit, means having a definite time interval in the operation thereof, and controlled by the fault-energized means for actuating the interrupter, and means for rendering the actuating means inoperative while the apparatus is operating.
3. In an electric circuit, the combination with an apparatus requiring a definite interval of time for the operation thereof and a 25 circuit interrupter therefor, of means energized upon the occurrence of a fault in the circuit, means, having a definite time interval in the operation thereof, controlled by the fault-energized means for actuating the 30 interrupter, and means for precluding the actuation of the interrupter by the definite-time means while the apparatus is operating.
4. In an electric circuit, the combination with an apparatus requiring a definite 35 interval of time for the operation thereof and a circuit interrupter therefor, of means energized upon the occurrence of a fault in the circuit, means controlled thereby for actuating the interrupter after an interval of time 40 greater than that required for the operation of the apparatus, and means for automatically extending the time interval, whenever necessary, until an operation has been completed.
5. In an electric circuit, the combination with a feeder circuit, a rolling mill for that 45 circuit requiring a definite interval of time for the operation thereof and a circuit interrupter for the circuit, of means for actuating the interrupter, means for controlling the time of operation of said means, and means for ensuring that the actuation of the interrupter by said means shall occur only when the apparatus has completed an operation 50 and is not operating.
6. In an electric circuit, the combination with a feeder circuit, a rolling mill therefor requiring a definite interval of time for the 55 operation thereof, and a circuit interrupter for the feeder circuit, of means for actuating the interrupter, means for controlling the actuating means having a time interval greater than that required for the operation of the rolling mill, and means for extending the time interval to the end of an operation, 70 if the interval should be completed while the mill is operating.
7. In an electric circuit, the combination with a feeder circuit, a rolling mill requiring a definite interval of time for the operation thereof, and a circuit interrupter for the feeder circuit, of means for actuating the interrupter, means for controlling the actuating means having a time interval greater than that required for the operation 75 of the rolling mill, and means energized while the apparatus is operating to prevent the actuation of the interrupter until its operation has been completed.
8. In an electric circuit, the combination with a feeder circuit, a rolling mill for that circuit requiring a definite interval of time for the operation thereof and a circuit interrupter for the feeder circuit, of means for actuating the interrupter, means for controlling the actuating means having a time interval greater than that required for the operation 80 of the rolling mill, and means for maintaining the interrupter-actuating means inoperative while the apparatus is operating.
9. In an electric circuit, the combination with an apparatus requiring a definite interval of time for the operation thereof, and a circuit interrupter therefor, of means energized upon the occurrence of a fault in the 85 circuit for actuating the interrupter, and means energized while the apparatus is in operation to maintain the actuating means inoperative during that time.
10. The combination with a rolling mill, a motor therefor, a source of energy for the motor and means for connecting the motor to the source of energy, of means for controlling the disconnection of the motor from the source of energy upon the occurrence 90 of a faulty condition in said source and means for rendering the controlling means ineffective during an operation of the rolling mill.
11. The combination with a rolling mill, a motor therefor, a source of energy for the motor and means for connecting the motor to the source of energy, of means responsive to an abnormal condition of the connecting means, and means responsive to the operating current of the motor while the mill is operating, said means co-operating to control the disconnection of the motor from its source of energy after the occurrence of a 95 faulty condition in the connecting means and after the completion of the operation of the rolling mill during which the faulty condition occurred.
12. The combination with an apparatus operating continuously through a predeter- 100

mined cycle, a motor for actuating the same, a source of energy for the motor, and a connecting device between the motor and the source of energy, of a relay responsive to 5 the motor current and a relay responsive to a predetermined abnormal condition in the source of energy or in the motor, for actuating the connecting device only after the apparatus has completed its operation 10 through the predetermined cycle.

13. The combination with an apparatus operating continuously through a predetermined cycle, a motor for actuating the same, a source of energy for the motor, and a connecting device between the motor and the source of energy, of means responsive to 15 the operating current of the motor for controlling the connecting device to disconnect the motor from the source of energy 20 only after the operation of the apparatus has been completed.

14. The combination with an apparatus operating continuously through a predetermined cycle, a motor for actuating the same, a source of energy for the motor, and a connecting device between the motor and the source of energy, of means responsive to the operating force of the motor for controlling the connecting device to disconnect the 25 motor from the source of energy after the completion of an operation during which an abnormal condition has occurred in the source of energy or in the motor.

15. In an electric circuit, the combination 30 with a motor energized therefrom and adapted to operate continuously through a predetermined operation, and a circuit-controlling device therebetween, of means re-

sponsive to the condition of the circuit and the motor and to the current traversing the 40 motor for controlling the circuit-controlling device only after the completion of an operation during which an abnormal or faulty condition should occur in the circuit or the motor.

16. The combination with an apparatus adapted for continuous operation during a predetermined cycle, an electric motor therefor and a source of energy for the motor, of means for disconnecting the motor from its 50 source of energy upon the occurrence of a fault in the motor or in the source of energy, and means for rendering the disconnecting means inoperative until the apparatus has completed the operation involved in 55 the predetermined cycle.

17. In an electric circuit, the combination with a motor operating an apparatus adapted to be loaded during a predetermined operation thereof, of means for disconnecting 60 the motor from the circuit and means for precluding such disconnection except when the apparatus is unloaded.

18. The combination with a continuously operating apparatus that is loaded at different times to perform predetermined operations, of a motor therefor, a source of energy for operating the motor, means for disconnecting the motor from its source of energy and means for precluding such disconnection while the apparatus is performing an operation.

In testimony whereof, I have hereunto subscribed my name this 11th day of January, 1921.

GOLDER P. WILSON.
